UNITED STATES PATENT OFFICE.

HENRY HELLMAN AND LEWIS CONDICT BAYLES, OF JOHANNESBURG, TRANSVAAL.

ROCK-DRILLING MACHINE OR ENGINE.

No. 888,497.

Specification of Letters Patent.

Patented May 26, 1908.

Application filed July 12, 1905. Serial No. 269,406.

To all whom it may concern:

Be it known that we, HENRY HELLMAN and LEWIS CONDICT BAYLES, citizens of the United States, both residing at Johannesburg, Transvaal, have invented certain new and useful Improvements in Rock-Drilling Machines or Engines, of which the following is a specification.

This invention relates to rock or like drilling or boring machines or engines actuated by means of compressed air or other expansive gaseous fluid, and has for its especial object the provision of means for introducing and conducting along the drill steel to the cutting extremity thereof a quantity of the actuating fluid and water.

Figure 1 is an elevation of the complete machine, showing in section the front portion of the power cylinder, the impact piece, 20 the swivel and the drill steel. Fig. 2 is a transverse section on line $y-y$ Fig. 1. Fig. 3 is a transverse section on line $x-x$, Fig. 1. Fig. 4 is a transverse section on line $x'-x'$ Fig. 1. Fig. 5 is a view of the swivel detached and shown open. Fig. 6 is a longitudinal section of the front portion of the power cylinder and protecting casing, showing a modified arrangement for supporting the drill shank in the forward end of the power cylinder; and Fig. 7 is an elevation of the shank end of the drill steel, showing a modified construction.

1 designates a hollow cylindrical protecting casing and 2 the power cylinder which is 35 slidably and rotatively mounted in said casing. Round the protecting casing 1 is clamped the sleeve or band 3, which is shown constructed with the cone 4 for mounting the apparatus in an ordinary column or other 40 suitable support. The sleeve 3 is split and formed, with the lugs 5 between which is placed a bolt 6 which serves for drawing the two lugs 5 together to tighten the sleeve 3 round the casing 1. The casing 1 is constructed with an inlet port 7 at or in proximity to the rear end, which serves for connecting an ordinary throttle valve through which the compressed air or other actuating fluid is admitted to the rear end of the casing 50 1. The casing 1 is also constructed at its forward end with holes 8 which serve as exhaust ports for the fluid exhausting into the casing 1 from the power cylinder 2.

The casing 1 is shown constructed of slightly smaller diameter at the forward end 55 to make a sliding fit with the exterior of the power cylinder 2. Instead of the construction shown it will be evident that a bush, cap or end piece may be fitted on or in the end of the casing to form a bearing for the forward 60 end of the power cylinder 2. The power cylinder 2 is counterbored or made of somewhat larger diameter at the forward end wherein is located the impact piece 10, which receives and transmits the impacts of the power piston 65 or percussive reciprocating member 11 to the shank of the drill or bit. The counterbore 12 forms with the bore 13 in which the power piston 11 reciprocates, an abutment or shoulder which limits the rearward movement of the impact piece 10. The counterbore 12 at the forward end is made taper and into it is fitted a taper bush 14, which is made with a square or polygonal parallel bore 15—see Fig. 3. The drill steel 16, is at 75 its forward extremity constructed with or fashioned into any ordinary and suitable form of drill or bit, as a "chisel" bit or "star" bit, and at its rear end or shank is made of square or polygonal section to correspond to 80 the bore 15 of the bush 14, in which it is loosely positioned. This construction insures the synchronous rotation of the bit 16 with the power cylinder 2 while allowing the bit 16 to move longitudinally of the power 85 cylinder 2 within certain limits. The inner end of the shank 17 abuts the forward end of the impact piece 10 in the working of the machine, so that the repeated impacts of the percussive reciprocating member 11 are immediately transmitted from the impact piece 10 to the shank of the drill steel 16.

The impact piece 10 is shown constructed with a central longitudinal hole or port 18 communicating at the rear end with the interior of the power cylinder 2 along which a quantity of the actuating fluid may pass from the forward end of the power cylinder 2. The drill steel 16 is also provided with a longitudinal hole or port 19 which coincides 95 with the hole 18 in the impact piece 10. The air or fluid passing from the power cylinder 2 through the impact piece 10 flows along the hole 19 in the drill steel 16 and escapes at or in proximity to the cutting extremity of the 100 drill.

The drill steel 16 is constructed with an annular enlargement or collar 20, and with a port (or ports) 21 in said collar communicating with the longitudinal hole 19. The port or ports 21 is or are preferably angularly disposed in relation to the longitudinal hole 19 and in a forward direction. Arranged round the collar 20 is a detachable swivel or swivel piece 22 (see Figs. 1, 4 and 5). The swivel is constructed of the two parts 23, 24, hinged together at 25. The two parts are connected to secure the swivel 22 round the collar 20, by means of a ferrule or nut, 26 which is carried by the one part 23 and slides up over the end of the other part 24 as seen in Fig. 4. A projecting pin 27, see Fig. 4, fixed in the part 23 works in a groove 28 in the inside of the ferrule 26. When the ferrule 26 is round the two parts 23, 24, or in the position in which it is shown in Fig. 4, it is retained in that position by rotating it part of a revolution to place the outer extremity of the pin 27 in a recess at one side of the groove 28. This provides a very ready means for clamping the swivel 22 in position on the drill steel 16. The swivel 22 is recessed on the inside to receive and fit the collar 20 and to form an annular space 29 round the collar; with this space 29 the port (or ports) 21 in the collar 20 communicates. The part 23 of the swivel is constructed with an extension 30 which forms a stem to which the hose or other flexible pipe 31 is fixed by means of the hose clamp or other suitable device 32. Through the extension 30 is formed a hole 33 leading into the annular space 29 round the collar 20. The other end of the hose pipe 31 is placed in a tank 34 containing water, or in communication with any other convenient 40 source of water supply.

When the machine is in operation, as previously explained a quantity of the actuating fluid passes through the hole 18 in the impact piece 10 and from the latter along the hole 19 in the drill steel 16 to the cutting end of the bit. This fluid in its passage over the port 21, exhausts the air from said port and from the annular space 29, hole 33 in the swivel and hose pipe 31, and by tending to 50 create a vacuum therein draws the water or allows it to be forced by atmospheric pressure from the tank 34 up the hose pipe 31 and through the hole 19 along which it passes with the actuating fluid to the cutting end of the drill. The water thus conducted to the bottom of the hole serves to prevent the formation of dust, and the fluid, which serves as the medium for conveying said water, by causing the water to impinge with some 60 force at the bottom of the hole, effectually ejects the cuttings, and by preventing their accumulation at the bottom of the hole obviates the sticking of the bit from this cause. By using a quantity of the actuating fluid in 65 this manner we find that a very much

smaller volume of water is required to eject the cuttings than would be the case were water under pressure used alone.

In Fig. 6 illustrative of a slight modification of the arrangement just described, the impact piece as a separate member is dispensed with. The power cylinder 2 at the forward end is constructed with a taper hole 12^a in which is fitted the bush 14^a formed with a hole of square or polygonal section. Between the bottom of the taper hole 12^a and the bore 13 of the cylinder 2 is formed a hole 13^a somewhat smaller in diameter than the bore 13. This hole 13^a places the bottom of the taper hole 12^a in communication with the forward end of the cylinder 2. The inner end 17^a of the drill steel 16 is made approximately of the same external diameter as the hole 13^a in which it fits, and beyond which it projects for a short distance into the bore 13 of the cylinder 2 so that it receives direct the impacts of the reciprocating percussive member 11. The steel 16 is constructed with the longitudinal hole 19 and with the collar or annular enlargement 20 in which is formed the angular or forwardly inclined hole 21 communicating with the longitudinal hole 19. The water swivel 22 may be secured round the collar 20 in the same manner as that previously described. 95

In Fig. 7, showing a modification of the construction of the drill steel 16 shown in Fig. 6, 17^a is the inner end which projects into the bore of the cylinder 2 and receives the impacts of the percussive reciprocating member 11; 17 is the part of square or polygonal section which fits into the polygonal hole 15 at the forward end of the power cylinder 2, and 19 is the hole formed longitudinally of the steel 16 along which the actuating fluid passes from the power cylinder. In the steel and in advance of the part 17 of polygonal section is formed a recess 20^a from which extends the angular and forwardly inclined port 21 which forms the water duct 110 communicating with the longitudinal hole 19. The water swivel 22 is located in the recess 20^a round the steel 16 so that the water may pass from between said swivel and the recess 20^a along the port 21 to the longitudinal hole 19. 115

What we claim as our invention and desire to protect by Letters Patent is:

1. In a rock-drilling machine or engine, a rotatable power cylinder, a drill steel slidably and non-rotatably held at the forward end of said power cylinder and having a passage extending longitudinally of said steel and communicating with the circumference of said steel, a swivel piece loosely surrounding said steel and in communication with the hole at the circumference thereof, and means for conducting liquid to said swivel piece. 120

2. In a rock-drilling machine or engine, a rotatable power cylinder, a drill steel slidably 125

and non-rotatably held at the forward end of said power cylinder and having a passage extending longitudinally of said steel and communicating with the circumference of
5 said steel and with the interior of the power cylinder, a swivel piece loosely surrounding said steel and in communication with the hole at the circumference thereof; and means for conducting liquid to said swivel piece.

In witness whereof we have hereunto set 10
our hands in the presence of two subscribing
witnesses.

HENRY HELLMAN.
LEWIS CONDICT BAYLES.
